PORATION OF DELAWARE

LIQUID PUMP

Application filed July 20, 1926. Serial No. 123,629.

This invention relates to the pumping of oil from a well and it particularly relates to equipment for operating a fluid-actuated pump.

The common form of pump used for pumping oil from a well consists of a reciprocating pump which is situated near the lower end of the well, the plunger of which is attached to the lower end of a string of sucker rods which extends upward through the well to the surface of the ground. The upper end of the string of sucker rods is usually connected to a walking beam by means of which the string of sucker rods is reciprocated and consequently the pump plunger is moved up and down. A greater percentage of the trouble with this form of pumping equipment is caused by the sucker rods, which by necessity are quite small in diameter and are very flexible. The trouble resulting from the sucker rods rises mainly from two sources, the sucker rods uncouple by reason of a rotation of the pump plunger, and the sucker rods break by reason of the variable stresses which are placed thereon. Fluid-operated pumps have been used to a certain extent, these being advantageous inasmuch as they do not require the use of a string of sucker rods and consequently do not have the troubles which accompany them. Fluid-operated pumps are characterized by the fact that the pump mechanism at the lower end of the well is operated by a fluid under pressure which is pumped down into the well from the surface of the ground.

It is an object of this invention to provide a novel arrangement of parts in a well for conducting the power-fluid for operating the pump to the fluid-actuated pump, and for conducting the pumped fluid to the surface of the ground.

Another object of our invention is to provide a pump for forcing the power-fluid into the well, which is operated by the walking beam crank of the derrick equipment.

A still further object of our invention is to provide a novel form of double acting pump.

Other objects and advantages will be made manifest hereinafter.

Referring to the drawings in which we illustrate our invention,

Fig. 1 is a diagrammatic view showing the upper end of our invention.

Fig. 2 is a view showing the lower end 55 of our invention.

Fig. 3 is a plan view of the power-fluid pump of our invention.

Fig. 4 is a longitudinal section of the power-fluid pump. 60

Fig. 5 is a section taken on the line 5—5 of Fig. 1.

Fig. 6 is a section taken on the line 6—6 of Fig. 1.

Fig. 7 is a section taken on the line 7—7 65 of Fig. 2.

Referring particularly to Figs. 1 and 2 of the drawings, the numeral 11 represents a well in which a water string indicated by the numeral 12 is installed. According to common practice, in the oil producing industry, the water string is installed before oil-bearing sands represented by the numeral 13 have been penetrated, the lower end of the water string 12 being cemented at 14 in order to exclude surface water from the well. Extending from the surface of the ground through the well inside the water string 12 is an oil string 15. The oil string 15 projects into the extreme lower end of the well through the oil-bearing sands 13, the lower end of the oil string 15 being provided in the form of a screen pipe 16. The upper end of the water string 12 is closed by a head-plate 18, and an annular gas space 19 is formed in the water string 12 around the oil string 15. A pipe 20 is connected to the upper end of the water string 12 for conducting gas from the gas space 19. Placed in the oil string 15 above the screen pipe 16 is a packer 22 which forms an outlet chamber 23 in the upper end of the oil string 15. Extending into the outlet chamber 23 is an oil tube 24, this oil tube 24 projecting through a cover-plate 25 which encloses the upper end of the oil string 15. The oil tube 24 provides a pressure chamber 27.

Connected to the lower end of the oil tube 24, which lower end is situated near the lower end of the outlet chamber 23 directly above 95 100

the packer 22, is a reducer 28. Connected to the lower end of the reducer 28 is a pipe 29 which extends through an opening in the packer 22 to the lower end of the well 11. 5 The pipe 29 is not in communication with the pressure chamber 27 but is connected to the outlet chamber 23 by openings 30 formed in the upper end of the pipe 29 directly below the reducer 28. Connected to the lower end 10 of the pipe 29 is a fluid-operated pump 32 which may be of any operable construction. The lower end of the fluid-operated pump 32 is provided with a customary form of gas anchor 33. The pipe 29 provides an outlet 15 passage 34 which is connected to the exhaust passage of the fluid-operated pump 32. An opening 36 is formed through the reducer 28, this opening communicating with the pressure chamber 27. Connected to the re- 20 ducer 28 in communication with the passage 36 is a pressure pipe 37. This pressure pipe 37 is quite small in diameter, as shown, and extends downward through the outlet passage 34, being connected to the fluid-operated 25 pump 32. The pressure pipe 37 is connected to the fluid-operated pump 32 in such a manner that the fluid under pressure supplied thereby will operate the mechanism (not shown) of the pump. Power-fluid is pumped 30 into the pressure chamber 27 through a power-fluid supply line 39 which is connected to the upper end of the oil tube 24 by means of a fitting 40.

Referring to Figs. 1, 3, 4, and 5, the number 45 represents a pressure-fluid pump which is situated in a derrick 46 of the well for the purpose of forcing fluid through the line 39 into the pressure chamber 27. The pump 45 consists of a barrel 48 and a plunger 49. The barrel 48 consists of a barrel member 50 in which a plunger sleeve 51 of the plunger 49 is adapted to reciprocate. The lower end of the barrel 48 is provided with a standing valve 52 which is seated by means 45 of a spring 53. A pivot block 55 is connected to an inlet T 56 which is positioned below the standing valve 52. The pivot block 55 is pivotally supported on a shaft 57 which is supported by a bracket 58. As shown in 50 Figs. 1 and 5, the bracket 58 is situated adjacent to a samson post 59 of the derrick 46. The barrel 48 is so supported that it may be pivotally swung in a vertical plane. The plunger sleeve 51 has a traveling valve 59 connected to the upper end thereof which is resiliently closed by a spring 60. Secured to the cage of the traveling valve 59 is a polish rod 61 of the plunger 49. This polish rod 61 extends through a stuffing box 62 of the barrel 48, which stuffing box is connected to an outlet T 63 of the barrel 48. A bearing block 65 is connected to the outer end of the polish rod 61. This bearing block 65 is placed on a pin 66 of a walking beam crank 67 of the derrick 46. The walking beam crank 67 is ordi-

nary derrick equipment and is secured to a shaft 68 which is rotated by means of a band wheel 69 secured thereto. When the walking beam crank 67 is in operation, the plunger 49 is reciprocated in the barrel 48 but the outer end thereof is moved through a circular path. For this reason the barrel 48 must be supported so that it will swing in a vertical plane with the plunger 49 as the walking beam crank 67 operates.

A fluid supply tank 71 is supported near the derrick 46 as shown, this fluid supply tank 71 being supplied with pumped fluid through a supply line 72 which extends from the upper end of the outlet chamber 23 formed in the upper end of the oil string 15. Fluid is conducted from the supply tank 71 to a suitable storage by means of a pipe 73. A flexible inlet line 74 is connected to the lower part of the supply tank 71 and is connected as shown clearly in Fig. 5, to the inlet T 56 of the pump barrel 48. As the pump operates, fluid is drawn into the lower end of the barrel through the flexible inlet line 74.

Connected to the outlet T 63 is a rigid outlet pipe 76. Positioned adjacent to the bracket 58 (Fig. 5) is a swivel joint 77 having parts 78 and 79 which are pivoted together on the same axis as the pivotal axis of the pump barrel 48. The member 78 of the swivel joint 77 is connected to the rigid outlet pipe 76, and the member 79 is connected to the supply line 39 which is connected by means of the fitting 40 to the upper end of the pressure chamber 27. The swivel joint 77 is absolutely necessary for the operation of the pump because of the fact that the rigid outlet pipe 76 must swing with the pump barrel 48. It would not be practical to make the outlet pipe 76 from a flexible tube, since it must carry a fluid under considerable pressure.

During the outward stroke of the plunger 49, fluid which in this case is oil, situated in the barrel 48 above the traveling valve 59, is forced therefrom through the outlet T 63 into the rigid outlet pipe 76. From thence it travels through the swivel joint 77, the power-fluid supply line 39 and the fitting 40, into the pressure chamber 27. During this time oil is drawn from the supply tank 71 through the flexible inlet 79 into the lower end of the barrel 48 which is below the traveling valve 59. During the inward or downward stroke of the plunger 49 the standing valve 52, which was previously open, immediately closes and the working valve 59, which was closed, is opened. Oil trapped in the space between the standing and working valves 52 and 59 is forced into the upper portion of the barrel above the traveling valve 59. It should be noted that since the polish rod 61 extends through the upper part of the barrel 48 the area thereof is substantially one-half the area of that portion of the barrel below the traveling valve 59. For this reason the pump 45

will be double acting; that is, oil will be pumped through the rigid outlet pipe 76 during both strokes of the plunger. This is true because the volume of oil forced into the upper part of the barrel 48 is twice the volume of the upper part of the barrel; therefore, one-half this oil must flow from the upper part of the barrel through the outlet T 63 and into the pressure chamber 27 through the interconnecting parts.

The fluid or oil under pressure in the pressure chamber 27 flows through the passage 36 of the reducer 28 into the pressure pipe 37 by means of which it is conducted to the fluid-operated pump 32. The fluid-operated pump, as previously described, may be of any common construction and it is therefore not necessary to show the construction thereof. This power-fluid operates the mechanism of the fluid-operated pump 32 and causes it to pump oil from the lower end of the well 11 upward through the outlet passage 34. The power-fluid is preferably exhausted into the outlet passage 34 and conducted to the surface of the ground with the pumped fluid. The pumped fluid passes upward through the outlet passage 34 and through the openings 30 into the outlet chamber 23. The oil flows upward through the outlet chamber 23 and passes into the pipe 72, by means of which it is conveyed to the supply tank 71. The supply tank 71 is kept full at all times so that a supply for the pump 45 will always be maintained. After the supply tank 71 is filled, however, the additional fluid pumped thereto will be conducted through the pipe 73 to a suitable storage or place of use. Any gas which may tend to collect in the well 11 passes upward around the oil string 15 into the gas space 19 formed

at the upper end of the well, this gas being conducted from the well through the pipe 20.

The arrangement of the piping in the well 11 is an important feature of the invention. The design is such that the construction is economical. The oil string 15 is always installed in a well immediately after the oil-bearing sand has been penetrated. When installing the parts of our invention the fluid-operated pump 32 is connected to the lower end of the pipe 29 and is lowered into the well, the small pressure-fluid pipe 37 being attached thereto at this time. The packer 22 is of common construction and is placed at the upper end of the pipe 29 and may be expanded into tight contact with the inner wall of the oil string 15 when the parts have arrived in proper position. As the fluid-operated pump 32 is being lowered into the well the reducer 28 and the oil tube 24 are connected to the upper end of the pipe 29. The use of the pressure-fluid pipe 28 is economical and may extend a greater portion of the length of the well. The features of using the reducer and connecting the pipe 29 to the lower end of the oil tube 24 is im-

portant to the invention, since it permits the use of a comparatively large outlet passage 34, which is desirable. The oil tube 24 provides a pressure chamber 27 in the upper end of the well and thus eliminates the necessity for providing a pressure-fluid tank at the surface of the ground.

The power-fluid pump 45 is a very important part of the invention. It is very simple in construction and is very efficient in pumping the fluid under pressure to the pressure chamber 27. A very important part of this pump is that it may be driven from the walking beam crank which is a usual part of the derrick equipment. The pump in itself is of small cost and does not require any additional driving means other than the walking beam crank 67 which is present at every well. An additional feature of the pump 45 is that it is double acting.

We claim as our invention:

In a pump of the character described, the combination of: a pump barrel; means for pivotally supporting said pump barrel; a pump plunger adapted to reciprocate in said pump barrel; a crank attached to said pump plunger for reciprocating said pump plunger in said pump barrel; a flexible inlet for said pump barrel; a swivel joint positioned on the pivotal axis of said pump barrel; and an outlet for said pump barrel connected to said swivel joint.

In testimony whereof, we have hereunto set our hands at Los Angeles, California, this 15th day of July, 1926.

BERNARD H. SCOTT,
SAMUEL E. ROSS.
